SIGNAL SYSTEM

Clarence E. Beach, Brookline, Mass., assignor to
 The Gamewell Company, Newton Upper Falls,
 Mass., a corporation of Massachusetts

Application November 5, 1931, Serial No. 573,151

24 Claims. (Cl. 177—367)

This invention relates to signaling systems and energy sources therefor, and is particularly suited for use where it is desirable that signaling systems shall accomplish results such as are generally contemplated by my prior Patent 1,528,596, for "Signal system", dated March 3, 1925, but where such signaling systems have functional characteristics and/or are subjected to service conditions which none of the energy sources disclosed by said patent fully meet in a satisfactory and continuously efficient manner.

For example, certain of the arrangements disclosed by said patent contemplate utilization of what is generally termed a "three-phase delta or star-connected energy supply", while other arrangements disclosed by said patent contemplate the use of a so-called "single-phase" alternating current, without any direct current mechanism. In the utilization of such arrangements, it is obvious that the electromagnets of instruments connected in the signaling circuit should be of a type which adapts them for energization by alternating current and it is therefore apparent that arrangements for utilization of single or multi-phase sources are unsuited for signaling circuits comprising instruments having electromagnet structure which does not operate satisfactorily with alternating current.

In many instances this is an important consideration; for example, where existing systems comprise a comparatively large number of instruments, as signal initiating stations, equipped with magnets unsuitable for energization by alternating current, or where it is desired to utilize in proposed new systems, without modification, types of instruments having successful service records extending over a large number of years, notwithstanding the fact that the types of instruments having such service records are, almost without exception, only obtainable on a commercial basis with magnets suited only for unidirectional current energization. In this connection it should be noted that most of the signaling instruments of the generally used commercial forms are of such design and arrangement that modification of the electromagnet structure is likely to involve changes in form and shape which would necessitate extensive rearrangement of parts and alteration of general dimensions, thereby precluding utilization of existing facilities for manufacture.

In addition to the foregoing considerations, there are situations where single-phase alternating current is available, but where multi-phase alternating current can be obtained, with ordi-

nary commercially available equipment, only with moving appliances such for example as rotary converters, and where the utilization of a constantly operating mechanism of such character is deemed objectionable, from various considerations such for example as impracticability of providing constant supervision.

Furthermore the arrangements disclosed by said prior patent for supplying energy to a signaling circuit from a single-phase alternating current source involve niceties of arrangements of relative inductance and resistance of alternative current paths which have been deemed objectionable in various instances as, for example, in the case of municipal fire-alarm systems in which the signal initiating stations comprise so-called "non-interference" electromagnets. Such magnets are normally shunted out of the series circuit but are brought into the circuit during activity of the mechanism, whereby the effect of the phase-splitting inductances at the central office may be objectionably disturbed if not substantially neutralized by inductance changes in the outside line, which renders it extremely difficult to maintain a desirable degree of equivalent mean effectiveness of the electromotive forces supplied between the ends of the metallic circuit and the ground.

In the aforesaid prior patent there are also disclosed arrangements for supplying the normally closed metallic path of a signaling circuit from a direct current source such as a battery, and for applying an alternating current potential between the metallic circuit and the ground, either through the connection of an alternating current source intermediate the battery terminals or by alternately grounding the terminals of the battery which normally supplies the metallic circuit. With the first-named arrangement satisfactory results have been obtainable only through use in the metallic circuit of instruments responsive to either direct or alternating current, while in the instance of the second arrangement deterioration of contacts for applying the ground connection to one side and the other of the normal current source and the maintenance of constantly operating mechanism of this character, have been deemed objectionable.

It is the general object of this invention to solve the problems just outlined and other problems inherent in previously proposed arrangements. More specifically it is one of the main objects of this invention to provide current supply equipment for signaling systems whereby energy from a two conductor alternating current

source is so applied to a three conductor utilization system that the potential between any one and another of the utilization conductors is unidirectional. It is a further important object to 5 provide such current supply equipment in which the mean value of the unidirectional potential applied between any one and another of the three utilization conductors is adequate for intended signaling purposes. Still another object 10 of this invention is to provide current supply equipment whereby energy from a two conductor alternating current source maintains a unidirectional current through a normally closed current path and also maintains a potential between 15 such current path and an associated conductor (such for example as the ground or the sheath of an underground cable), whereby leakage between such circuit and conductor may be instantly manifested without thereby impairing 20 the effectiveness of the normally closed circuit for signaling purposes.

In another aspect the present invention has the further object, in order to meet certain service conditions, to provide unidirectional current 25 for energizing certain of the utilization conductors while at least one of the conductors is energized by alternating current, whereas in other situations, where it is altogether undesirable, alternating current may be excluded from the 30 controlling magnets of the instruments in all of the current paths, unidirectional current being substituted therefor.

In a still further aspect the invention provides means for employing a plurality of rectifier units 35 with a two conductor alternating current source so that, for each of a plurality of utilization conductors, at least one rectifier unit is interposed between the conductor and the source of alternating current.

40 Other objects and features of the present invention will be apparent from the following detailed description illustrating the genus of the invention by explaining several concrete embodiments thereof which are illustrated in the 45 accompanying drawings in which:

Fig. 1 is a circuit diagram illustrating the principal aspect of the invention;

Fig. 2 is a similar diagram illustrating a modification using only unidirectional instruments;

50 Figs. 3 to 5 are diagrammatic representations illustrating the operation of the new system under different conditions;

Fig. 6 shows curves which approximately illustrate the configuration of the current flowing in 55 different paths of a system according to the invention, during various conditions thereof; and

Figs. 7 to 11 are circuit diagrams similar to Fig. 1, but somewhat simplified, showing various modifications of the invention.

60 Referring to Fig. 1, A, B and C are representatives of a number of signal initiating means, herein shortly referred to as alarm boxes, or stations, which are connected in series with the receiving station terminals 26, 27 by conductors 21, 22, 23, 24 forming, with the alarm boxes, an outer circuit or loop. The signal initiating stations A, B and C may be of any known type having facilities for effecting the formulation of impulses in a normally closed electric circuit representing desired code signals, together with facilities operable in every case, or at certain times for grounding the normal metallic circuit during such impulses.

75 The signal initiating station A, which repre-

sents the simplest type of signal station suitable for operation with a circuit according to the invention, and is described in my aforementioned Patent No. 1,528,596, comprises contacts 51, 52 and 53 actuated by a code wheel 58 in such a 5 manner that under normal or inoperative condition of the box, contacts 51 and 52 are closed, thereby completing the series circuit of signaling means and receiving appliances, whereas, upon operating the box (usually referred to as "pulling a box"), all three contacts 51, 52, 53 are first connected when 51 is lifted by a cam of wheel 58, and then disconnected when 51 is descending after having passed over the cam. The opening of all three contacts interrupts the closed circuit 15 for normal signaling, whereas the interconnection of all three contacts grounds the circuit for emergency signaling, each signal impulse comprising a grounding and an interruption.

The diagram of signal initiating station B represents the current paths provided in signaling stations functionally similar to the type of station disclosed by my prior patent for "Successive non-interference signal box", dated January 2, 1917, No. 1,210,398 and comprises a non-interference electromagnet 42, shunting contacts 41, code wheel operable contacts 47 for signaling over the normal metallic circuit, contacts 43, 46 and 50 cooperating with segments 44 and 45, and contacts 49 for establishing ground connection. 30 Upon pulling box B contacts 41, which normally close the series circuit around the devices of the box, are opened, thus bringing the non-interference magnet 42 and the signaling contacts 47 (normally closed) into operative relationship 35 with the circuit. Magnet 42 is thereupon energized and, assuming that the system is in normal condition, permits signaling over the usual or normal metallic current path, which is initiated by code wheel 48. The wheel opens and 40 closes contacts 47, thereby opening and again closing the signaling circuit according to the code signal assigned to this box, and upon completion of the sending cycle, the box is restored to normal condition. It is well understood in 45 the art, and fully described in my aforementioned United States Patent No. 1,210,398, that non-interference magnet 42 renders its box ineffective to interfere with the signals sent by the other boxes of the circuit if B should be pulled 50 when any of these boxes are sending. During operation when the circuit is in abnormal condition each signal impulse establishes connection of one or the other side of the line to ground, as described in the above identified patent.

The station C is representative of stations having functional characteristics similar to those of the mechanism shown and described in the patent to F. W. Cole, No. 553,838, for "Successive non-interference signal box", dated February 60 4, 1896, comprising normally closed contacts 31 for shunting the electro-magnet windings while the box is at rest, contacts 35 and 36 for normal signaling over the metallic circuit, and non-interference magnet windings 33 and connecting contacts 39, windings 33 being connected across contacts 31. The outside terminals of 65 33 are connected to contacts 35 and 36 respectively which are arranged for interconnection therebetween and with the wheel contact 37 incident to the engagement therewith of the teeth of the code wheel 38. The normally open contact 39 is operable by the box mechanism to effect closure of the normally open ground connection. Contacts 35 and 36 are for normal sig- 75

naling when contacts 39 are open. However, when the latter are closed during emergency operation, each connection between 35 and 36 is accompanied by a connection with ground over 5 37 and 39, whereas if 35 and 36 are disconnected, the ground is also opened with respect to each of the contacts 35 and 36. Instead of employing contacts 35, 36 and 37 as shown, a contact arrangement similar to that of box A (contacts 51, 52, 53) may be incorporated in a box 10 of this type.

The receiving station, connected with the outer circuit at 26 and 27, comprises four asymmetric conductors 1, 2, 3 and 4 of suitable type, 15 hereinafter referred to as rectifiers, which are connected in a bridge circuit with terminals 111, 112, 113, 114 intermediate the rectifiers which conduct current substantially only in the direction of the arrows of their symbols. The 20 opposite terminals 111, 112 are connected over the secondary winding 7 of a transformer T having a primary winding 6 which is supplied over terminals 9 and 10 from a suitable source of single-phase alternating current, as for example a single phase alternating current generator 7'. It is, however, understood that, for 25 purposes of this invention, the secondary 7 constitutes the real source of current, the references herein to "an alternating current source" 30 being intended to signify any instrumentalities employed for applying an alternating electromotive force between the portions of the circuit to which the ends of winding 7 are shown to be connected.

35 A resistance 8 may be inserted in series between winding 7 and terminal 111. Terminal 111 is also connected to one terminal of a manifesting device G of conventional design, whose other terminal is grounded, this arrangement 40 providing a common return conductor from any grounded point of the outer circuit to the receiving station. The two other opposite terminals 114, 113 of the rectifier bridge are connected to two manifesting devices E and F and these to 45 the receiving station terminals 26 and 27 which are joined to the incoming ends of the outer circuit, so that 113 and 114 join the power supply with a normally closed signal circuit loop including signal initiating and manifesting 50 devices.

In the embodiment shown in Fig. 1, the manifesting device G must be of the "universal" type, that is responsive to both alternating and unidirectional current, whereas E and F as well as the magnets of the signaling boxes need only be 55 operative with unidirectional current, whereby the term "unidirectional", as employed throughout this specification as defining direction of potential or current flow applied to or in a given current path, is used to distinguish from alternating current, potential or current flow, in the sense of the significant or practical effect of such potential or current flow, as distinguished from what might be considered, under some circumstances, as the apparent potential or the theoretical potential or current flow developed or occurring, for example, incidental to certain uses of asymmetrically conducting units.

It is sometimes feasible and desirable to employ exclusively apparatus responsive to unidirectional current not only in the outer circuit but also in the manifesting circuit, and such an arrangement is shown in Fig. 2. This circuit has alarm boxes A, B and C of suitable design, and two unidirectional manifesting de-

vices e and f with magnets 61 and 62 and armatures 65 and 66 normally attracted by the magnets continuously energized by the closed signal circuit. Magnet 63 and armature 67 are of similar unidirectional design but normally de- 5 energized and released respectively. Magnet 63 is part of another rectifier bridge comprising rectifiers 11, 12, 13 and 14, being connected across the opposite terminals 73 and 74 of that bridge. The two other opposite terminals 71 and 72 of 10 the bridge are connected to ground and to terminal 111 of the current supply bridge respectively; such bridge and magnet arrangement constituting the third manifesting device g. Aside from the different arrangement of the 15 grounded manifesting device Figs. 1 and 2 are in general principle identical and it is evident that the current flow in magnet 63 is always unidirectional no matter what its direction may be in the ground conductor. This feature is also 20 brought out by the arrows indicating the current flow of Fig. 5.

The conventional register shown in Fig. 2 by way of example comprises pens 171, 172 and 173 attached to resilient arms 175, 176 and 177 25 which are normally lifted from the recording tape t whereas, if armatures 65 and 66 are released, pens 171 and 172 contact with the tape upon swinging over stops 81 and 82 and bending back again from the tape. Similarly, pen 173 30 in cooperation with stop 83 marks the tape upon armature 67 being attracted and then released by magnet 63. It will of course be understood that this particular manifesting device is merely described as a comparatively simple example of 35 such apparatus and that any other suitable arrangement may be employed.

The operation of the new system under normal and various faulty line conditions will now be described with particular reference to Figs. 3 40 to 6, Figs. 3, 4, and 5 being simplified diagrams, with current paths, of an installation according to Fig. 2.

Under normal non-signaling conditions, when the series circuit of the line is closed within each 45 alarm box and not grounded and when the line is sound (Fig. 3), if the transformer secondary 7 is energized, in the direction of arrow 131, by one half cycle of an alternating current having a general configuration according to curve 101 50 of Fig. 6, the valves of the rectifier bridge permit current flow only as indicated by full line arrows: from terminal 111, over rectifier 3, terminal 113, manifesting device f, line, manifesting device e, terminal 114, rectifier 4, terminal 112, and thence 55 back to 7. During the next half cycle, when current flow is in the direction of the dotted arrow 132, the current is conducted from terminal 112 over rectifier 2, terminal 113, manifesting device f, line, manifesting device e, terminal 114, 60 rectifier 1 and terminal 111 back to 7, as indicated by dotted arrows. It is evident that in the absence of inductance in the current path, the current flowing in the outer circuit would have the general configuration of curve 102 of Fig. 6, 65 that is, the current would be composed of a unidirectional series of alternate half waves resulting from rectification of an original alternating current such as is represented by curve 101.

Since the signaling current path, for example 70 from terminal 113 (Fig. 3) through f—A—B—C—e to 114 includes both inductance and resistance, the shape of the current pulsating in this circuit corresponds not strictly to that of pulsating electromotive force 102, but is in addition in- 75

- fluenced by induced electromotive forces, counteracting, or supporting electromotive force 102 during the latter's increase and decrease, respectively.
- 5 During the valleys of curve 102 (representing the rectified exciting electromotive force), the supporting electromotive force due to the inductive resistance of the electromagnets of the signalling circuit induces a current, herein referred to as circulating current, which has two paths, namely (referring for example to Fig. 3) from the line through e—114—1—111—3—113—f back to the line, and from the line through e—114—4—112—2—113—f back to the line. In this 10 manner a circulating path comprising two concurrently effective parallel conductors is provided, each parallel conductor excluding the alternating current source, and including two rectifier units in series, all rectifiers being conductive 15 in the same direction within the circulating path. It is evident that the presence of this direct circulating path, which is free from the impedance of the transformer secondary, enhances the effectiveness of the induced current for smoothing 20 the rectified current due to the impressed unidirectional electromotive force. The approximate shape of the smoothed current is indicated at 102' of Fig. 6. If an alarm box, for example B, is pulled, it interrupts the closed signal circuit 25 and operates manifesting devices e and f as above described. With this type of box, as well as with a type corresponding to box C, the ground is disconnected during normal operation and device g therefore not affected, whereas box A 30 grounds the system with every signal impulse, with a resulting current flow operating also manifesting device G, in a manner which will be easily understood from the following discussion of operation under faulty circuit conditions.
- 35 Should the signal circuit be broken at a point a as indicated in Figs. 1 and 4, the electromagnets of manifesting devices e and f would be deenergized, and such devices would thereupon act to indicate that the circuit had been broken. While 40 the normal current path was thus interrupted, activity of any boxes such as A, B and C would cause the formulation of a series of signaling impulses effective through that portion of the circuit which remains unimpaired between the active 45 box and the central office, and thence through the ground. In the case of box A, such signaling current path would become effective due to the fact that this box establishes a ground connection 50 incidental to each signaling impulse. In the instance of box B, because, due to the broken line condition, no current would be flowing in the normal path, the non-interference magnet 42 would fail to become energized when the shunting contacts 41 are opened, so that the succeeding 55 operation of the mechanism would in due time effect closure of the ground current path and thereby enable the mechanism to send the intended signal through the ground and whichever side of the circuit remained unimpaired, utilizing 60 contacts 43 to 46, 49 and 50 as described at length in Patent #1,210,398. In the instance of box C, there would be corresponding action due to actuation of contacts 39 as more fully described in Patent #553,838.
- 65 70 As mentioned before, when the conditions of the system are normal, that is when the usual metallic current path is closed, and no signal is in course of formulation, a current path is established from one terminal of the secondary winding 7 of the transformer through rectifier 2

or rectifier 3 (depending upon the direction of current flow in winding 7) to terminal 113, thence through manifesting device f, through boxes A, B and C, manifesting device e, terminal 114 and rectifier 1 or 4 (again depending upon the direction of current flow through secondary winding 7) and the other terminal of winding 7.

So long as the current path just traced is maintained, the electromagnets of the manifesting devices e and f are effectively energized; but upon interruption of this current path as by a circuit break at a, the electromagnet windings of the manifesting devices e and f become deenergized and remain so, either until the normal current path is restored or until an emergency current 15 path is established through the ground connections. However, if such an emergency path is established from the portion of the circuit extending from break a to manifesting device f, the electromagnet windings of device f, are effectively energized, but the electromagnet windings of the manifesting device e are not energized. Correspondingly, if the portion of the circuit between break a and manifesting device e is connected, the electromagnet of device e is effectively 20 energized but that of manifesting device f remains deenergized. If, while the circuit remains broken at a, ground connections are applied to the portions of the circuit at both sides of the break, the electromagnets of both manifesting 25 devices e and f are effectively energized. Theoretically, the characteristics of the current flow incidental to closure through the ground of a broken line at one side or the other of the break, might be represented by the curve 103 of Fig. 6 30 (in the absence of inductance in the current path) since only one series of alternating half cycles of the alternating current is operative in this circuit, the other series being ineffective since the line is open at a. This theoretical current is diagrammatically indicated by the rectangular dashes of Fig. 4, and flows from secondary 7 through 112—2—113—f—operative line portion—A—B—ground g—111 back to 7. Similarly as explained when describing normal signalling conditions with reference to Fig. 3, the inductance of the signalling circuit induces electromotive forces which have the same direction as isolated half waves 103 during the intervals between these half waves. The corresponding induced currents flow 40 in an unobstructed circulating path analogous to that traced for Fig. 3, but in this case including a grounded point and the emergency conductor. The path and the approximate configuration of this induced current are indicated by the 45 pointed dashes of Fig. 4 and it follows that the manifesting devices g and f, as well as the non-interference magnets of the alarm boxes, are in this manner supplied with a reasonably smooth unidirectional current flowing in the same direction as during normal operation and approximately indicated by curve 105 of Fig. 6.

Describing now the actual signaling, and referring again more particularly to box B by way of example, the continuously deenergized non-interference magnet 42, establishes a circuit closed over ground by first connecting contact 46 with 43 whereupon 42 is energized over normally closed contacts 47, and starts rotation of code wheel 48 which opens and closes contacts 47 as under normal operating conditions, with the difference that the circuit is now closed over 46, 44, 43 and 49 to ground instead of relying upon the normal path over wire 21 to the adjacent box. At the conclusion of the sending operation, 75

contacts 49 are opened and 43 is in neutral position. It is of course irrelevant at which place of the line the break occurs. For example, if the break should occur at *b* at the other side of box B, the operation is quite analogous, with the only difference that the alternate set of half ways of impressed electromotive force (curve 104 of Fig. 6) is now effective. The magnetically induced circulating current flows during the ineffective 10 half cycles of the alternating current source through a circulating path including rectifier 1, and smooths out the half cycle series indicated at 104. In this case manifesting devices *e* and *g* respond.

15 It is well known that ground connections have in most cases a higher resistance than the normal metallic signaling circuit, and it will now be evident that the present system has the following advantage related to this fact. In order to provide under both normal and abnormal conditions signaling currents of approximately similar magnitudes, it is desirable to apply a higher electromotive force when signaling through ground than for operating with the normal circuit. In the present instance (referring for example to Fig. 1) the normal circuit is supplied through rectifiers 1 and 2, or 3 and 4 in series, during respective half cycles, which devices cause a certain fall of potential. On the other hand, 30 when the ground connection is closed, the output of the secondary winding 7 need pass through but one rectifier unit at any given time. Thus, for example, when the direction of current flow in secondary 7 is toward terminal 111, the path then effective extends from said terminal through the ground to terminal 114, and thence through rectifier unit 4 to terminal 112 of secondary 7. During the next half cycle, the current path passes from this secondary coil through terminal 40 112, rectifier unit 2, terminal 113, the right-hand portion of the circuit shown, and back through the ground to terminal 111, which contacts with the opposite end of the winding 7 without passing through a second rectifier unit.

45 From the foregoing it is apparent that the non-interference and succession effects of alarm boxes, for example of the type of box B, are effective under the described emergency operation. For example, with a break at *a*, box B being pulled, and subsequently also an adjacent box of similar design between box B and terminal 21, the non-interference magnet of the adjacent box would be caused by the signaling of B not to permit signaling by its box over the emergency path presented by B. However, as soon as B completes its signaling, the other or "seeking" box encounters the same faulty condition as B originally did, and proceeds to send emergency signals similar to B.

60 Assuming that, with the line broken at *a*, box B is first pulled and then box C, these boxes would in due time act to apply their respective ground connections, and such action of box B would tend to prevent effective energization of the non-interference magnet 33 of box C. When, however, box B completed the formulation of its intended signal and thereupon opened its ground connection, the non-interference magnet 33 of box C would be energized, and thereby effect release of the signaling contacts 35, so that the subsequent actuation of these contacts by the wheel 38 would cause intended response of the manifesting devices *f* and *g*.

75 The operation of alarm boxes of the type A

and C will be easily understood in view of the foregoing, and the prior descriptions of these devices.

Another possible faulty condition is in the nature of leakage to ground, for example if the line is grounded at *c* as indicated in Figs. 1 and 5. Tracing the current flow in the system under such conditions, from the terminals 111 and 112 of the transformer secondary 7, when the alternating current in 7 flows during a certain series 10 of alternate half cycle periods from 111 towards 112, its path continues from 112 over rectifier 2, manifesting device *f* and the right side or branch of the line to *c*, branches there on the one side from *c* over ground and manifesting device *g* to 15 terminal 111, and on the other side from *c* over the left side or branch of the line, manifesting device *e* and rectifier 1 also to 111. The current flow during this half cycle series is indicated in Fig. 5 with full arrows. During the alternate 20 half cycle series, when the current in 7 flows from 112 towards 111, it continues on the one side from 111 over rectifier 3, terminal 113, *f* and the right branch of the line to *c*, and on the other side from 111 over *g* and ground also to *c*. From 25 *c*, there is a common path for this half cycle series from *c* over the left branch of the line, *e* and 4 to 112. This half cycle series is indicated in Fig. 5 with dotted arrows.

Due to the branching of the current paths, the 30 line branches carry unequal amounts of current, since part of the flow is always diverted over ground. For example, during the half cycle series whose current flow is indicated by full arrows, the left-hand line branch (in parallel with the ground 35 connection) carries less current than the right-hand line branch. The magnitude of this current is diagrammatically indicated at *m* of curve 106 of Fig. 6, curve 106 symbolizing the current flow in the left-hand branch. The larger 40 current simultaneously flowing in the right-hand branch is indicated at *n* of curve 107 which symbolizes the current flow in the right-hand branch. Similarly, during the alternate series of half cycles, the left-hand branch carries more current 45 than the right-hand branch, as indicated by *o* and *p* of curves 106 and 107. These currents are again smoothed out (as approximately indicated in curves 106 and 107), due to currents induced by the inductances in the respective circuits and 50 flowing through circulating paths unobstructed by the impedance of the alternating current source. The ground connection, through which the current can flow in both directions, carries a current composed of components having the 55 approximate configuration of curves 106 and 107, one of these curves however being reversed, the resultant having the approximate configuration of curve 101. Therefore, if the line is grounded, and although none of the alarm boxes is operated, 60 the current in the ground connection energizes manifesting device *g*, which is normally deenergized if the system is sound, thereby indicating a trouble condition, and also its nature. Manifesting devices *e* and *f* remain energized, as under 65 normal, ungrounded line conditions. Also, in a system according to Fig. 1, the instrument *g* must be capable of being responsive to alternating current and unidirectional current whereas, if the circuits are organized according to Fig. 2 with 70 a second rectifier loop for the manifesting magnet 63, this magnet only needs to respond to unidirectional current, so that, in this case, only unidirectional instruments, or magnets, are required.

The above described condition of the normally 75

closed signaling system continues so long as the latter is grounded at any point thereof, and, in addition to indicating the fault as hereinbefore discussed, it permits signaling in the following manner. Assuming that the ground is established at *c* as indicated in Figs. 1 and 5, between box *c* and terminal 26, any signals originating in boxes A, B and C are manifested only by device *f* since *e* and *g* remain continuously energized by the unidirectional half wave series which flows over ground condition and left-hand line branch and can not be interrupted by signal impulses of any of these boxes. Similarly, if the ground occurs at a point between box A and terminal 24, manifesting devices *f* and *g* are continuously energized, whereas signals are received by *e*. Further, if the system is grounded at any point intermediate the alarm boxes, any box can successfully send signals, which will be manifested at either *e* or *f*, depending upon the location of the signaling box with respect to the ground, the manifestation being always in the line branch of the signaling box.

Concerning the operativeness of non-interference devices in case of a ground anywhere at the line, it is evident from the preceding description, that, in spite of the ground, current is always present in all parts of the circuit so that these devices are operative within their respective sections of the line regardless of the ground. For example, if the line is grounded at *d* between A and B, alarm box A manifests its signals at *f*, and boxes B and C manifest their signals at *e*, with proper separation of their respective codes if they should be simultaneously pulled. Still further, the signals are kept apart even if all three boxes are pulled simultaneously, box A manifesting at *f* and boxes B and C manifesting at *e* in orderly sequence, due to the action of their non-interference devices. Also, the ground connection does not substantially affect the strength of the current in the line. For example, conductors *d*—ground—111 and *d*—line—114 are in parallel, and both in series with *d*—line—113, during one of the two series of alternate unidirectional half cycles. 111 being approximately the electrical midpoint of the current supply system, and *d*—ground—111 (being substantially without resistance), while augmenting the normal current in *d*—line—113, does not substantially affect the current strength in *d*—line—114, so that all three manifesting devices, *e*, *f*, *g* are sufficiently energized. Similarly, conductors *d*—ground—111 and *d*—line—113 are in parallel, and together in series with *d*—line—114, during the other series of half waves. Consequently, if, with a ground at *d*, box A is pulled, manifesting device *f* records the current interruption according to the code, which *e* and *g* remain energized; and if boxes B and/or C are pulled, *e* records, with *g* and *f* stationary. The hereinbefore mentioned feature that, if the line is grounded at *d*, box A can initiate signals at *f* and subsequently, or at the same time, boxes B and/or C can manifest at *e*, is explained from another point of view by the above described fact that alternate sides of the line circuit are in series, and parallel with the ground connection, during alternate half cycles, so that each half operates independently, but with current of the same direction, during alternating time intervals corresponding to alternate series of half cycles. However, if boxes at different sides of the ground, as for example A and B in relation to ground *d*, are simultaneously pulled, manifest-

ing device *g* is deenergized every time when A and B interrupt the line simultaneously, since during such simultaneous interruption, both alternate series of half cycles are inoperative and the whole system, ground conductor included, is without current. However, manifestations of this nature at *g* will be easily interpreted as incidental, or rather indicative of simultaneous operation of boxes at both sides of a ground, since both devices *e* and *f* manifest at the same time clearly intelligible signals coming from these boxes.

Recapitulating, it may be said that a ground divides a circuit according to this invention into two separate, and for practical purposes independent signaling circuits, the signal initiating and manifesting means in each circuit performing independently of those of the other circuit, including the well known features of "successive non-interference" operation, but all operated by unidirectional current of the same nature.

Another possible faulty condition is a short circuit, for example connecting points *a* and *b* of Fig. 1. Such a short circuit substantially deprives all alarm boxes of line current, and, so long as none of these boxes are operated, E and F are energized, and G deenergized. Upon pulling one of them, for example box C, the following circuits are established during each grounding impulse of the box. Considering first one of the alternate series of unidirectional half cycles, the current of one such series flows from 7 through 112—2—113—F—21—24—b to *a*. At *a*, the circuit branches, one branch going from *a* through 23—26—E—114—1 to 111, and the other branch from *a* through C—ground—G also to 111, the circuit being closed from 111 through 8 to 7. The other series of unidirectional half waves flows from 7, in opposite direction, to 111 where the circuit branches. One branch goes from 111 through 3—113—F—21—24—b to *a* and the other branch from 111 through G—ground—C to *a*. From *a*, the circuit continues through 23—26—F—114—4—112 to 7. Thus, manifesting devices E and F remain energized, but device G responds to the signals from C at each interruption of the ground-line connection at C. Upon pulling box C, its magnet is not energized since no line current is present in C, so that it is permitted immediately to establish ground connection for emergency signaling by closing contacts 39, whereupon the code wheel starts to initiate the impulses. Upon completion of its signaling operation, box C again restores its mechanism to normal.

From the foregoing it is also evident that the circuit is similarly operative in case of short circuits bridging less than all boxes, between *a* and *b* as assumed above, but bridging any box singly or any number of boxes collectively, in any position within the circuit.

Under certain operating conditions it has been found that a resistance, such as 8, favorably influences the cooperation of the rectifier with the various conditions which may develop in the signaling circuit and it was also found that changes in the relative positions of resistance and ground conductor may be desirable, depending upon the peculiar characteristics inherent in each particular installation. For example, the ground circuit may be connected directly to the rectifier bridge as shown in Fig. 1, or it may be connected between transformer secondary and resistance, as shown in Fig. 7. The difference of these two arrangements is not one of principle, but merely

changes circuit characteristics under emergency operation, one or the other characteristic being preferable for individual installations. The difference of emergency circuit characteristics depending upon the use of installations either of Fig. 1 or Fig. 7 is the following one. It has been discussed at length especially with reference to Fig. 5, that the emergency manifesting device G can be either, during one alternate half cycle series, in parallel with the right-hand line and together with the latter, in series with the left-hand line, (dotted arrows of Fig. 5) or, during the other series of half cycles, in parallel with the left-hand line, and together with the latter, in series with the right-hand line (full arrows of Fig. 5). Considering now resistance 8 in relation with these emergency circuits, it appears that in a connection according to Fig. 1, the resistance is always included in series with the manifesting device G and one side of the line but never in shunt with G, which is sometimes called a "long-series short-shunt" connection. On the other hand, in an installation according to Fig. 7, the resistance is in "short-series long-shunt" connection, that is, the manifesting device G alone is in series with one side of the line, while G and the resistance in series are in shunt with the other side of the line. As mentioned before, one or the other arrangement may be preferable 30 in order to assure favorable emergency current distribution in a particular installation.

In certain installations it may be desirable to omit one of the manifesting devices for normal operation, for example F of Fig. 1, and to substitute for the ground manifesting device G a ground defector instrument D. Such an arrangement is shown in Fig. 8, somewhat simplified. In an installation of this type, ground trouble is detected by D, while signal manifestation takes place only through instrument E. Normal operation is as explained in connection with Fig. 3, the only difference being that signals are received at E only. If a break should occur at a, only the boxes between E and a remain operative, with a half wave series in the circuit from terminal 112 through 111—D—ground—signaling box—E—114 to 112. As shown in Fig. 4, only the manifesting device which is at the same side of the break as the signaling box receives current, so that, since only one receiving device is provided, only signals from boxes at one side of the break can be received.

When the signal loop or any part thereof is grounded, the current distribution is exactly as shown in Fig. 5, and since, in that circuit, signals from any point of the loop are received at both manifesting devices e and f, it will be evident that any signal despatched under these conditions in a circuit according to Fig. 8 actuates relay E, the ground being indicated by detector D.

Signals from short-circuited boxes can not be received since, as will now be evident from the above description of signaling under such conditions with reference to Fig. 1, signals from short-circuited boxes can only actuate manifesting devices in the emergency conductor. Sometimes, it may be desirable to make D sufficiently sensitive to indicate currents of low strength. In this case, unless a second valve arrangement according to Fig. 2 is provided, instrument D should have high resistance and be operative for both unidirectional and alternating current. Device E will then generally not be operative in series with D, since E requires a current of a higher

magnitude than that sufficient to operate D. In every other respect, an arrangement according to Fig. 8 functions in the same manner as an installation according to Figs. 1 or 2.

The embodiment illustrated in Fig. 9 may have advantages under certain conditions. It comprises a transformer with a primary 6 and a secondary 7 divided in two sections 97 and 98 by a tap 94. The terminals 121 and 122 of the transformer secondary are connected over asymmetric conductors 92 and 93, terminal 123, manifesting device F, line with alarm boxes A, B, C and manifesting device E back to tap 94 of the transformer secondary. One terminal of the transformer secondary is also directly connected to ground. Under normal conditions, a circuit of this nature supplies the line with full wave unidirectional current substantially according to curve 102 of Fig. 6, whereby signals sent by the alarm boxes are manifested through E and F. The current of one half wave series flows from 94 through secondary 97, terminal 121—93—123—F—A—B—C—E—91 back to 94, and the current of the other half wave series flows in circuit 94—98—122—92—123—F—A—B—C—E—91—94.

If a break occurs in the line, for example at a, the relay at the same side of the break as the sending box responds, actuated by one half wave series. For example, if box B is pulled, current flows from ground through 121—97—98—122—92—123—F—A—B back to ground, signals being received at F. If box C should be pulled, current flows in the other direction from 94 through 97—121—ground—C—E—91—94, signals being received at E. During a trouble ground or emergency signaling ground an alternating current composed of alternate half wave series in the line branches flows through ground to terminal 121. Assuming the ground to be at d, one half wave series flow from 94 to 121 and branches there into 121—ground d, and 121—93—123—F—A—d, continuing through d—B—C—E—91 to 94. The other half wave flows in circuit 121—97—94—98—122—92—123—F—A—d; first branch d—ground—121—97—94, second branch d—B—C—E—91—94.

The non-interference means of the alarm boxes will also operate substantially in the same manner. However, the absence of a manifesting device in the ground conductor relieves all manifestations of changes in the circuit to devices E and F which respond similarly to the corresponding elements of Fig. 1. In contradistinction from the heretofore discussed arrangements, the currents flowing in the line branches separated by a ground c may be of different strength. For example, assuming that, during a certain half cycle series (when the left-hand branch is parallel with the ground conductor and, together with the latter, in series with the right-hand branch), the current flows from 121 towards 122, and that the line is somewhere grounded, the whole transformer secondary 7 is effective in the circuit comprising 121, 7, 122, 92, 123, F, line, and ground c back to 121. On the other hand, the alternate half wave series will be practically absent from the same branch, which is during this period substantially in shunt with ground. Analogous conditions prevail upon the left-hand branch of the grounded circuit, where the alternate half cycle (corresponding to the period when ground and right-hand branch are in parallel, and together in series, with the left-hand branch), is in addition suppressed by valve 91. However, irrespective of this alternate shunting of the branches over ground, the devices E

50 to devices E and F which respond similarly to the corresponding elements of Fig. 1. In contradistinction from the heretofore discussed arrangements, the currents flowing in the line branches separated by a ground c may be of different strength. For example, assuming that, during a certain half cycle series (when the left-hand branch is parallel with the ground conductor and, together with the latter, in series with the right-hand branch), the current flows from 121 towards 122, and that the line is somewhere grounded, the whole transformer secondary 7 is effective in the circuit comprising 121, 7, 122, 92, 123, F, line, and ground c back to 121. On the other hand, the alternate half wave series will be practically absent from the same branch, which is during this period substantially in shunt with ground. Analogous conditions prevail upon the left-hand branch of the grounded circuit, where the alternate half cycle (corresponding to the period when ground and right-hand branch are in parallel, and together in series, with the left-hand branch), is in addition suppressed by valve 91. However, irrespective of this alternate shunting of the branches over ground, the devices E

and F remain operative with their respective series of half cycles.

If any box or boxes are short circuited no signals originating therein can be received since, as explained before, under these conditions signals can only be received in the emergency conductor.

Still another embodiment of the invention is shown in Fig. 10, which differs from the arrangement according to Fig. 9 chiefly by omitting the rectifier in the lead to the midpoint of the transformer secondary and the manifesting device in the same branch, and by employing a ground detector D in the ground connection.

Again, the circuit is normally energized with full wave rectified current flowing in the circuits traced above when describing the normal operation of the circuit according to Fig. 9, and signals can be normally received by device F.

If the line is broken, signals can only be received in a circuit including device F, and only if the signaling box is between the break and F, exactly as described in connection with Fig. 9.

At the presence of a ground, or when emergency signaling over ground takes place, this circuit performs similarly to that of Fig. 9. During the half cycle when the current in 7 flows from 121 toward 122, the connection over ground from c to 121 is in series with 97—98—122—92—123—F—line, and in parallel with the left-hand line branch leading from the ground to 94, the entire transformer secondary 7 being active, and the current in the right-hand branch being augmented due to the resistance of instrument D. During the alternate series of cycles, when the current flows from 97 towards 121, the ground connection is in parallel with 94—97—121—93—123—F—line and both are in series with the left-hand branch, but the current will be weaker since only the half winding 97 is active. Consequently, instrument D is energized by alternating current whose opposite half cycles are of unequal amplitude. Furthermore, the left-hand branch carries alternating current, since the loop circuit 121—97—94—line—ground—121 contains no asymmetric element. In the case of a short circuit, signals from short-circuited boxes can not be received, as explained in connection with Fig. 9.

The arrangement according to Fig. 11 differs from that of Fig. 7 mainly in the omission of rectifier 1, so that the circuit under normal conditions carries only one series of alternate half cycles due to the electromotive force in the direction from 112 to 111, these half wave series flowing from 112 through 111—113—F—line—E—114 back to 112. It will now be evident that in case of a break, signals are received at E and G from boxes between E and the break, and at F and G from a box between F and the break. For example, if a break exists at a, and box C is pulled, signaling through ground, current of one half wave series flows from 112 through 7—G—ground—C—E—114 back to 112. If box B, on the other side of a is pulled, current of the other half wave series flows from 7 through 112—113—F—A—B—ground—G back to 7.

If the line is grounded at any point, for example d, the following right and left branched paths exist: One half wave series flows from 7 through 112—113—F—A—d—G back to 7. The other half wave series flows from 112 through 7 and from there in two branches, G—ground—d and 8—111—113—F—A—d, where both branches unite and continue, through B—C—E—114 to 112 and back to 7. Due to the presence of resistance

8, it can be assumed that said right and left paths, respectively, carry alternate half cycle series and the ground conductor alternating current. Therefore, manifesting devices E, F and G operate similarly as explained in connection with Fig. 7. In the case of short-circuited boxes, any such box is able to despatch signals through ground, to be received at device G, right-hand and left-hand branches, respectively, carry alternate series of half cycles, as will be apparent from Fig. 11. Manifesting devices, E, F and G operate similar to those in the arrangement according to Fig. 7.

Configuration of the signaling currents, as employed in this invention, is of minor importance, provided they are unidirectional at every point where instruments which respond to such current only are employed. The shape of the current impulses is of minor importance because the magnitude of the current frequency is very much higher than that of the transmission rate of the signals which are ordinarily sent over systems of this type, and also, as pointed out hereinbefore, because the inductance of the system smooths the unidirectional current waves, not only those of the fully rectified current, but also the series of alternate cycles.

It is apparent from the foregoing description that the present invention permits successful emergency operation not only under the faulty conditions which have been expressly discussed, but also under other more or less similar troubles or combinations thereof. For instance, emergency signaling is possible irrespective of the fact whether a fault occurs upon the line between the alarm boxes, or within the boxes, or upon the lines leading from the boxes to the central station. Also, signaling is possible if for example, two gaps, two grounds, a gap and a ground, or a gap and a short circuit, etc., exist, with the exception of a few so-called electrically hopeless cases, where boxes are situated between two circuit faults such as grounds and/or breaks.

It should be understood that the present disclosure is for the purpose of illustration only and that this invention includes all modifications and equivalents which fall within the scope of the appended claims.

I claim:

1. Means comprising terminals for operatively associating a source of alternating current with a three-conductor utilization system, comprising four asymmetric valves connected as a full wave rectifier bridge for excitation from a source of single phase alternating current, the terminals of said source being connected between respective pairs of valves, and two of the utilization conductors being connected between intermediate pairs of valves applying unidirectional energy representative of both of the half waves of the applied alternating current between said two utilization conductors, a connection from the third utilization conductor directly to one of the alternating current source terminals, and means for connecting and disconnecting any combination of two or three of said conductors, whereby a series of half cycles of said supply may be applied between said third conductor and one of the first named two utilization conductors, and the alternate series of half waves between said third conductor and the other of said two conductors, and whereby unidirectional paths may be established exclusive of the alternating current supply, said paths being constantly available from each

- utilization conductor to one and the other of the two remaining utilization conductors.
2. A two-conductor alternating current source and a three-conductor utilization system, in combination with connections involving asymmetric valve equipment interposed between said source and said conductors for applying from said source a unidirectional electromotive force derived from both half waves of said source between two of said utilization conductors and an electromotive force derived from the half waves of one direction, of said source, between one of said two and the third of said utilization conductors, and providing a path independent of said source from said one of said two to said third of said utilization conductors.
3. A signaling system utilizing a circuit including the inductive windings of electromagnets suited for energization only by unidirectional current flow, signal initiating stations serially included in such circuit and involving facilities for establishing ground connections therat, a grounded alternating current supply source and rectifying means connecting said source with said circuit so as to supply substantially unidirectional current thereto and to provide paths which exclude said source for conduction of circulating current through said circuit and between respective sides of said circuit and the ground.
4. In a signal system, an alternating current source, a conductor and a signaling current loop including signal manifesting devices therein adjacent to the ends thereof and signal initiating stations each comprising means for governing the effectiveness of a connection between said conductor and said loop, and rectifying means having input and output terminals, said input terminals being connected to said source and said output terminals and one of said input terminals being connected to the ends of said loop and to said conductor, respectively.
5. In a signal system, an alternating current source, a conductor and a signaling current loop including signal initiating stations each comprising means for formulating a code signal and for governing the effectiveness of a connection between said conductor and said loop, rectifying means having two input terminals connected to said source, and two output terminals, one input terminal and the output terminals respectively connected with said conductor and the ends of said loop, and manifesting mechanism suitably associated with one or more of said connections.
6. In a signal system, rectifying means having input and output terminals, a signaling current loop including signal initiating stations, manifesting means connected between the respective ends of said loop and said output terminals, a conductor through which emergency connection may be established with said loop through one or more of said stations, and a manifesting device connected between said conductor and one of the input terminals of said rectifying means.
7. In a signal system, a pair of alternating current supply conductors, a signaling loop having provisions whereby it may be connected to ground and including signaling devices responsive to unidirectional current flow, and four asymmetrically conducting rectifying units, one of which units is connected for conducting current from one end of said loop to one of said supply conductors, another unit from said end of said loop to the ground and to the other of said supply conductors, and the remaining two units from the respective supply conductors to the other end of said loop.
8. Current supply equipment for applying energy from a two-conductor alternating current source to a three-conductor utilization system, comprising three asymmetrically conducting rectifying units, one of which units is connected for conducting current from one of said utilization conductors to one of said source conductors, another unit from said one to another of said utilization conductors, and the remaining unit from one of the source conductors to the third utilization conductor, a connection between the second named utilization conductor and the second source conductor, and means for formulating signaling impulses through paths resultant from serial connections between different pairs of said system conductors.
9. Means for operatively associating a two-conductor source of alternating current with a three-conductor utilization system comprising a current path between a utilization system conductor and an alternating current source conductor, current paths between the other two utilization system conductors and the other source conductor and between one of said two utilization conductors and said first named source conductor, asymmetric valve equipment included in said first and last named paths and in one only of said second named paths to facilitate unidirectional current flow through a path including said source, said first named path and said one of said last named paths as well as through paths excluding said source and extending between said one of said last named utilization conductors and respective ones of the other utilization conductors, and means for formulating signaling impulses through paths resultant from serial connections between different pairs of said system conductors.
10. A signal system comprising an alternating current source, a signaling current path having two terminals, a conductor and provisions whereby it may be connected to a point of said path, and means connected to said terminals supplying thereto substantially unidirectional current flow from said source and urging alternate current flow, derived from the entire electromotive force of succeeding half-waves of said source, between said conductor and the respective terminals of said path.
11. A signal system comprising an alternating current source, a signaling current path having two terminals and signal initiating means and signal manifesting means therebetween, a conductor including signal manifesting means through which an emergency connection may be established between said source and said path, and means connected to said terminals for supplying thereto substantially unidirectional current flow from said source and urging alternate current flow, derived from the entire electromotive force of succeeding half-waves of said source, through circuits formed by said conductor and the portions of said path on respective sides of an emergency connection.
12. A signal system comprising an alternating current source, a normally closed circuit having signal initiating means and signal manifesting means in series therein, a conductor through which an emergency connection may be established between said source and any point of said circuit, and means for applying unidirectional current impulses from said source to said manifesting means through said conductor and an associated part of said circuit, and for supplying a substantially continuous unidirectional current

- to said manifesting means through said circuit independently of said conductor.
13. A signal system comprising an alternating current source, a signaling current path having two terminals, a signaling current conductor having provisions whereby it may be connected with said path, and means for continuously supplying a substantially unidirectional electromotive force, derived from succeeding half-waves of said source, to said terminals and for applying the entire electromotive force of alternate half-waves of said source between said conductor and respective terminals of said path, the resultant direction of the electromotive force applied to various portions of said path being unaffected by the establishment of said emergency connection.
14. Means for operatively associating a source of single phase alternating current with a three-conductor utilization system comprising connections between the first and second system conductors and one terminal of said source and connections between said second and the third system conductors and the other terminal of said source, and asymmetric conductors in each of said connections between said second named conductor and the respective terminals of said source, means for formulating signaling impulses through paths resultant from serial connections between different pairs of said system conductors, one of said asymmetric conductors providing a unidirectional current path between said second and third system conductors and between one of said last named system conductors and said second named terminal.
15. Means for operatively associating a source of single phase alternating current with a three-conductor utilization system, comprising a connection between one system conductor and one terminal of said source and connections between the other system conductors and the other terminal of said source, an asymmetric conductor in said first named connection, an asymmetric conductor in one of said second named connections, and an asymmetric conductor between said first named terminal and the system conductor associated with said one of said second named connections, means for formulating signaling impulses through paths resultant from serial connections between different pairs of said system conductors, said asymmetric conductors providing a unidirectional current path from said source through said first connection and one of said other connections, and between said first system conductor and said system conductor associated with said one of said second named connections.
16. A signal system comprising a source of alternating current, a signaling loop having terminals, a conductor through which emergency connections may be selectively established with various portions of said loop, current detecting means in said conductor operative with unidirectional current, rectifying means associated with said conductor for supplying said detecting means with unidirectional current, and rectifying means associated with said source for supplying said terminals of said loop with unidirectional current and supplying alternating current between said conductor and either one of said terminals.
17. In a signal system, a signaling loop having provisions whereby it may be connected to ground, an alternating current source, and full wave rectifying means having two input terminals connected to said source and two output terminals, said output terminals being connected to the respective ends of said loop for supplying substantially unidirectional current thereto and one of said input terminals being connected to ground.
18. In central office equipment for use in a signaling system of the type having a signaling current path and a ground or common return conductor at times connected to said path, comprising terminals for the respective ends of said path and a third terminal for said conductor, an alternating current source, connections between said source and respective ones of said terminals, the connections to two of said terminals respectively including unidirectional conducting means and being so applied to said source as to urge current flow of one series of half waves between such two terminals passing in a certain direction through a predetermined one of said connections, and the remaining connection including unidirectional conducting means and being so applied to said source as to urge current flow of the other series of half waves between such connection and said predetermined one of the first named two connections, said current flow passing through said predetermined one of said connections in the opposite direction, and signal manifesting means responsive to current flow in respective ones of said first named two connections.
19. Central office equipment for use in signaling systems of the type where a signaling current path and a ground or common return conductor may at times be connected, comprising terminals for the respective ends of said path and a third terminal for said conductor, a source of alternating current, connections between the first and second path terminals and one terminal of said source and connections between said second and the ground terminal and the other source terminal, asymmetric conductors in each of said connections between said second named terminal and the respective source terminals, one of said asymmetric conductors providing a unidirectional current path between said second path terminal and said ground terminal, and between one of said path terminals and said second named source terminal.
20. The combination of a full wave bridge rectifier for applying energy from a two conductor alternating current source to the terminals of a direct current signaling circuit and a third terminal, two electro-responsive devices connected between direct current output terminals of said rectifier and respective ones of said terminals, and a connection from said source to said third terminal, whereby establishment of a connection between said first named terminals will cause full wave rectified current flow through both of said responsive devices and establishment of a connection between one of said first named terminals and said third named terminal will cause half-wave unidirectional current flow through one of said devices and establishment of a connection between the other of said first named terminals and said third terminal will cause half-wave unidirectional current flow through the other of said devices.
21. Central office equipment for a direct current emergency signaling system comprising rectifying means for applying energy from a two conductor alternating current source to three terminals of a direct current circuit, and electro-responsive devices serially connected between direct current output terminals of said rectifying means and respective ones of two of said terminals, said rectifying means comprising asymmetric

conductors connected between said source and said devices whereby establishment of a connection between said first named terminals will cause full wave rectified current flow through both of said responsive devices and establishment of a connection between one of said first named terminals and said third named terminal will cause half-wave unidirectional current flow through one of said devices and establishment of a connection between the other of said first named terminals and said third terminal will cause half-wave unidirectional current flow through the other of said devices.

22. In a signaling system utilizing a source of alternating electromotive force and comprising three conductors which may at times be connected in any combination of two or three, means for applying consecutive one-half cycles of substantially full alternating electromotive force from said source between one of said conductors and the other two conductors, alternately, and said full alternating electromotive force between said other two conductors.

23. A current supply equipment comprising full wave rectifying means for applying energy from a two conductor alternating current source to a three conductor utilization system which utilization conductors may at times be interconnected in any combination of two or three, said rectifying means being connected between the source conductors and two of said utilization conductors and the third utilization conductor being connected to one of said two source conductors. 5

24. In a signal system, an alternating current source, rectifying means having input terminals connected to said source and output terminals, a plurality of signal initiating stations, a circuit connected to said output terminals including said 15 signal initiating stations, and a conductor through which emergency connection may be established between one of said input terminals of said rectifying means and said circuit through one or more of said signal initiating stations. 10

CLARENCE E. BEACH.
